UNITED STATES PATENT OFFICE.

JOHN ALLEN HEANY, OF WASHINGTON, DISTRICT OF COLUMBIA.

FLUID-PRESSURE DRILL.

1,084,009.

Specification of Letters Patent. Patented Jan. 13, 1914.

Application filed April 8, 1913. Serial No. 759,675.

To all whom it may concern:

Be it known that I, JOHN ALLEN HEANY, a citizen of the United States, and a resident of Washington, in the District of Columbia, have invented certain new and useful Improvements in Fluid-Pressure Drills, of which the following is a full and clear specification, reference being had to the accompanying drawings, in which—

10 Figure 1 is a longitudinal sectional view of my valve mechanism complete; and Fig. 2 a similar view taken on the line 2—2 of Fig. 1.

15 The object of this invention is to provide a simple and efficient automatic pneumatic valve mechanism for reversing the action of the tool piston, as more fully hereinafter set forth.

20 The letter *a* designates the usual cylinder of a pneumatic rock drill provided with the usual combined inlet and exhaust ports *b*; *c* the usual tool piston and *d* the usual rod for operating, or for connection to, the drill or other tool.

25 Extending along one side of the piston *c* is a casing *e* which is formed into a cylinder *f* at each end, the inner end of each of these cylinders being closed by the body of the casing and its outer end by a suitable

30 cap or plug *g*. The outer end of each of these cylinders is in communication with the adjacent end of the cylinder *a* by one of the aforesaid ports *b*. At opposite sides of each port *b* is affixed a pair of rings *h* whose inner cylindrical faces form valve seats for a piston valve *i* which is connected by a rod *j* to a motor piston *k*, which latter works in a lining *l* fixed in the cylinder *f* at the inner end thereof. The piston *k* is larger in diameter than the piston valve *i*, and the inner face of the piston *k* is greater in pressure-area than the outer face thereof to the extent of the area of the connecting piston *i*.

35 The connecting rod or member *j* is smaller in diameter than the piston valve *i*, and to the space thus formed between the two pistons *i* and *k* is connected a fluid pressure supply conduit *m*. The two supply conduits *m* are brought to the center of the casing and are adapted to be put into communication with the supply *n* by ports *o* and *p* in a rotary plug *q* mounted in the casing, the arrangement of ports being such that when the pressure is cut off from one of the ports *m* it will be cut off from both of them.

40 A transverse branch *r* of the port *p* is

adapted, when ports *o* register with ports *n*, to communicate with a port *s* in the casing and this port *s* communicates with lateral ports *t* which extend respectively to the upper ends of two transverse cylinders formed in the body of the casing. In each of these cylinders works a reciprocating cylindrical valve *u*, each valve having sliding contact with a lining sleeve *v* fixed in each cylinder. 45 A coil spring *w* normally presses each valve inwardly, that is, toward the engine cylinder *a*. When each valve *u* is at the outer extremity of its stroke, an annular flange *x* on its outer end opens port *t*, and when said 50 valve is in its normal, inner position said flange *x* closes said port *t*. When each of said valves *u* is at the inner end of its stroke it puts the inner end of the adjacent cylinder *e* into communication with the atmosphere through a port *y*, annular groove *y'* in valve *u* and a casing port *y''* and when in its outer position it closes said port *y*. The inner end of each valve *u* normally extends 55 through a hole in the cylinder *a* and into the path of the tool piston *c*, the contacting parts of the piston and the valves being suitably beveled, so that the reciprocation of the piston *c* will alternately actuate the 60 valves *u*.

55 The piston *c* is sufficiently long, with respect to the working length of the cylinder *a* and the distance between the two valves *u*, that the piston will preferably at all times hold one of the valves *u* in its out position. 65 When the plug *q* is turned so as to bring the ports *m* and *t* into communication with the pressure supply, the compressed air will pass into the inner end of that one of the cylinders *f* whose inlet port *v'* happens to 70 be uncovered by the annular flange *x*, whereupon the piston *k* in that cylinder will be moved toward the outer end of the cylinder. This movement of the piston *k* will move 75 piston *i* out of the inner ring *h* and into the opposite ring seat *h* and thus put the supply conduit *m* into communication with the adjacent end of the engine cylinder through port *b*. The piston *c* will then move toward 80 the opposite end of the main cylinder and during its movement it will open the closed valve *u* and release the open valve *u*, whereupon the released valve will close and thus permit the inner end of its adjacent cylinder *f* to exhaust through port *y*. The piston 85 holds one of the valves *u* in its open position until the piston opens or is about to open 90

the other valve u , and as each valve is thus opened by the piston a sufficient quantity of compressed air is allowed to pass into the inner end of a cylinder f to actuate its piston valve i in a manner to put the pressure supply into communication with the adjacent end of the engine cylinder. The piston valves i are brought back to exhausting position, (in which position the parts are as shown at the left hand end of Fig. 1) by pressure of air on the outer face of its piston k , which pressure moves the piston k to the inner end of its cylinder and thus draws piston valve i into its inner ring h , thereby putting the cylinder exhaust port b into communication with the atmosphere through the exhaust port a' in the cylinder head g . It will be observed that supply pressure is always upon the outer face of each piston k so that this piston at all times normally tends to move inwardly to exhausting position. This constant pressure is overcome, by reason of the greater pressure area on the inner face of the piston, when pressure is admitted into the inner end of the cylinder f .

It will be understood that the power of the blow may be regulated by means of the main valve plug q . To regulate the speed I provide an auxiliary plug b' , which is rotatably mounted in the casing e adjacent to the main plug q and is provided with ports which adapt it to register with ports s and t , so that by turning this plug b' more or less air may be permitted to enter the cylinders e through the ports t and thus regulate the speed of the tool by regulating the speed of movement of the valve pistons i . It will be also understood that the usual or any improved mechanism may be employed for rotating the tool carrying piston, this means in my drawing being designated as a whole by the letter c' . This means for rotating the piston performs the additional function in my apparatus of constantly bringing new parts of the surface of the piston into contact with the tappet ends of the auxiliary valve u so as to thereby avoid wearing grooves in the face of the piston.

By the arrangement of auxiliary or pilot valves u shown it will be observed that I am enabled to greatly shorten the tool piston, and this shortening of the piston greatly decreases its weight and thus permits an increase of speed with a given air pressure. Another feature of importance is that by my valve arrangement I reduce to a minimum the clearance between the distributing valves i and the interior of the work cylinder and thus provide for a material saving in live air. The amount of clearance in my apparatus is represented by the space between the surface of the distributing valve i in its cut off position and the interior wall 65 of the work cylinder. Another feature of

importance is that each auxiliary valve controls both an inlet and an exhaust port of the motor cylinders f whereas in every other apparatus of this class that I am aware of the exhaust from the motor cylinder is provided for by simply a leak port which is always open to the atmosphere; it will thus be seen that by my arrangement I provide for a considerable saving of air as but a modicum of air will be sufficient to actuate the distributing valve.

Having thus described my invention, what I claim as new, and desire to secure by Letters Patent, is—

1. In combination, a main cylinder and a tool piston working therein, said cylinder having a combined inlet and exhaust port at each end, a distributing valve at each end of the cylinder adapted to open and close one of said ports at a point near the end of the cylinder, and means for pneumatically actuating said distributing valves said means being located intermediate the distributing valves.

2. In combination with a main cylinder and piston, distributing valves at the ends of the cylinder, and means intermediate the distributing valves for pneumatically actuating these distributing valves, said means consisting of a differential piston motor connected to each of said valves, means for subjecting one side of the differential piston to supply pressure constantly, and auxiliary valves for intermittently subjecting the other side of the differential piston to supply pressure.

3. In combination with a work cylinder and piston, distributing valves therefor and means for alternately opening and closing these distributing valves, said means consisting of a motor cylinder adjacent each valve, a differential piston in each motor cylinder connected to the adjacent distributing valves, a conduit being provided for constantly subjecting one side of said motor piston to supply pressure during the operation of the apparatus, and devices for intermittently admitting an exhausting air to the opposite ends of said motor cylinder, these devices consisting of an inlet port for each cylinder and an exhaust port therefor and an automatically operated auxiliary valve for controlling said ports.

4. In combination with a main cylinder and piston, distributing valves for said cylinder, means for actuating said valves embodying a pair of auxiliary valves, manual means for varying the power by controlling the supply of air directly to the distributing valves, and independently operable manual means for varying the speed by controlling the admission of air to the auxiliary valves.

5. In combination with a main cylinder having inlet and outlet ports at its ends, a distributing valve controlling each of said

ports and located directly at the point where the port enters the end of the cylinder, means for actuating said valves independently consisting of a motor cylinder and 5 piston and a pair of auxiliary valves arranged to project into the cylinder at points opposite mid-length thereof, whereby said auxiliary valves may be brought compara-

tively close together and thus enable a tool piston of minimum length to be employed. 10

In testimony whereof, I hereunto affix my signature in the presence of two witnesses.

JOHN ALLEN HEANY.
